UNITED STATES PATENT OFFICE

WALTER PARKS, OF DENVER, COLORADO, ASSIGNOR TO VAPOR CAR HEATING COMPANY, OF CHICAGO, ILLINOIS, A CORPORATION OF NEW YORK

VAPOR REGULATOR

Application filed August 19, 1929. Serial No. 387,002.

This invention relates to atmospheric pressure or vapor steam heating systems, especially for railway cars; and the purpose of the invention is to provide certain improvements in the construction of the steam regulator, commonly called vapor regulator, for reducing and controlling the flow of steam from the train line to the radiator or radiators of the car in response to the temperature of the heating medium adjacent the outlet of the system, whereby the sensitiveness and accuracy and functioning of the regulator are increased, and the heating system made more efficient and economical in its operation.

One of the specific objects of the invention is to provide a steam regulator in which the controlling valve is opened against the train pipe pressure, by a construction of the device which does not require such a close packing of the valve stem, or other operating element, as might affect the sensitiveness of response of the valve to changes in temperature of the heating medium in contact with the governing thermostat.

Another object is to provide the regulator with two consecutively opening and closing valves, a main valve and a pilot valve as they may be called; this arrangement being advantageous particularly in the case of a regulator designed to work against train pipe pressures which are frequently high.

Another object is to provide for completely, or substantially completely, enclosing the thermostat so that its operation is not affected and made irregular by air currents which are necessarily variable in accordance with the speed of the train.

Another object is to provide a steam regulator in which the valve or valves are closed by the expansion of a thermostatic member and opened, against train line steam pressure, by a spring which is located outside of the steam spaces of the instrument so as not to be affected by the deteriorating influence of steam temperatures.

Other incidental objects will be referred to in the following description of the preferred embodiment of my invention illustrated in the accompanying drawings, in which—

Fig. 1 is a view in elevation of a part of a car heating system employing a steam regulator constructed in accordance with the present invention.

Fig. 2 is a longitudinal sectional view of the steam regulator.

Fig. 3 is a cross sectional view, with the scale enlarged, on line 3—3 of Fig. 2.

Figs. 4 and 5 are fragmentary vertical sectional views of the upper portion of the regulator, Fig. 4 showing both main and pivot valves closed, and Fig. 5 the main valve closed, but the pilot valve open.

Fig. 6 is a view in perspective of the valve stem or operating rod for seating and unseating the consecutively operated valves.

Fig. 7 is a view in perspective of the element which provides the port between the high and low pressure chambers of the regulator, and

Fig. 8 is a similar view of the spring for unseating the controlling valves when the thermostat contracts.

Referring first to Fig. 1, A designates the steam train pipe of the car, the flooring of which is indicated at B. C is a supply pipe from train line A to the steam regulator D, and E is a pipe from the low pressure side of the steam regulator to the radiator valve F, which is assumed to be the common four-way valve to which the inlet and return ends G, H are connected. J is a pipe leading from the radiator valve F to the thermostat chamber of the steam regulator D, and K is a drip pipe or nipple at the bottom of the thermostat chamber of the regulator, which nipple is preferably furnished with a flexible extension L, intended, in practice, to extend down within a few inches of the track, the rails of which are indicated at M.

Referring now to Figs. 2, 3, 6, 7 and 8, the steam regulator comprises a housing 10 for the thermostatic member which consists preferably of a capsule or hollow diaphragm 11, the housing being provided with a lower removable section 12 secured to the fixed section 10 by a clamping bolt 13 which passes through perforated ears 14 and 15 on the fixed and removable sections. Preferably, to prevent tampering with the adjustment of the

thermostatic member, the clamping bolt 13 is sealed to the drip nipple K by a wire seal 16, which passes through perforations 17 and 18 in the head of the bolt and in the nipple, respectively. Pipe J from the discharge end of the radiator is tapped into the wall of housing 10.

The thermostatic diaphragm 11 consists of a pair of flexible metal discs 18 and 19 secured to upper and lower blocks 20, 21, and having their edges beaded together at 22 and sealed with solder 23. The capsule thus formed is seated on the upper end 24 of the drip nipple K, which latter is formed with discharge openings 25 for the discharge of water of condensation.

A bracket 10^a formed on the side of the housing 10 supports a valve casing 26 integrally formed with the housing and bracket, which is divided to provide a high pressure chamber 27 to which pipe C leads and a low pressure chamber 28 with which pipe E leading to the radiator valve F is connected. A port and seat forming member 29 (Fig. 7) having a threaded portion 30 is screwed into the web 31 intervening chambers 27 and 28. Member 29 is formed with a smooth cylindrical surface 32 to receive the end of a screen 33. The squared end 34 of member 29 provides a seat for the main valve 35. The main valve 35 and the secondary or pilot valve 36 are operated by a rod 37, which extends through a packing gland 38 in the end wall 39 of the valve casing 26 and has fixed thereto a clevis member 40 provided with a cross pin 41. The cross pin is engaged by the notched portion 42 of a bellcrank 43, which is formed with a hub 44 pivoted by the pin 45 between the arms of a bracket member 46 formed on valve casing 26. A hair pin spring 47 (Fig. 8) bears with its loop end in a groove 48 on the end of the bellcrank 43, the other ends of the spring being seated in grooves 49 in the upstanding web 50 formed on valve chamber 26. The intervening portions of the spring lie in grooves 51 on the under side of the hub 44 of the bellcrank, (Fig. 3). An operating rod 52 is pivoted at 53 to the bellcrank. The lower end of this rod is in the form of a socket 54, and seats on the upper block 20 of the thermostatic diaphragm 11 over a boss 55 on said block.

The operating rod or valve stem 37 is formed near its inner end with a set of radial ribs 56 and also a set of ribs 57 of smaller radial dimension. The ribs 56 guide the rod 37 in the port which extends through member 29. The main valve 35 is slidably arranged upon the ribs 57 of the valve stem 37. The inner end of the valve stem is threaded, as indicated at 58, for the locking nuts 59, which hold the pilot valve 36 on the rod against the ends of the ribs 57.

The operation of the steam regulator above described is as follows: Fig. 2 shows the posi-

tion of the movable parts of the radiator when the system is cold. The thermostatic diaphragm 11 is contracted and valves 35, 36 are unseated. When the steam is turned on, it passes from the train pipe A through pipe C to the high pressure chamber 27 and then through and around the screen 33 and through the port in member 29 into the low pressure chamber 28 and thence to the radiator through pipe E and the four-way valve F. Water of condensation from the radiator passes through pipe J to the thermostat housing 10 and out through the openings 25 and drip pipe L. With the system in operation on a fairly cold day, there will preferably be enough condensate formed to seal openings 25 so that the thermostat will be completely enclosed and protected against air drafts, which would constitute a variable factor, depending upon the speed of the train, in the functioning of the thermostat were the thermostat to any extent exposed to such drafts. In the ordinary operation of the heating system the temperature of the condensate will not be high enough to expand the thermostat. As soon, however, as steam reaches the thermostat housing, through pipe J, the thermostat will expand lifting rod 52 and rocking the bellcrank 43 against the tension of spring 47 so as to draw the valve stem 37 to the left, as shown in Fig. 2. Valve 35 will first be seated under the pressure of steam in chamber 27, against the end of member 29; and ultimately if the expansion of the thermostat is sufficient, valve 36 will be moved to its seat against valve 35. As the throttling of the port will involve a diminution of steam inflow resulting in the diminution of or cessation of steam flow to the thermostat chamber, when the system has been in operation for a certain time, the controlling valves will be in a balanced position admitting just enough steam to the system to make up for radiation losses. Assuming, however, that the valves are both seated (the condition illustrated in Fig. 4) the opening of the valves, which takes place when thermostat 11 contracts, is brought about by spring 47 aided by the weight of the bellcrank 43 and rod 52, against the train pipe steam pressure which may be very high. By providing a pilot valve 36 which opens before the main valve 35 is unseated, so as to balance pressure on opposite sides of the main valve, the operation against train pipe pressure is facilitated. Because the valve is small the spring will open it against any ordinary train pipe pressure. Under normal conditions of operation, after the system has been started up, the main valve may remain seated and control be effected entirely through the movements of the pilot valve.

It will be observed that the member which operates the valves 35, 36, that is to say, the reciprocating rod 37, enters the high pres-

sure chamber 27 from the low pressure chamber 28, the rod being mounted slidably in the end wall 39 of the low pressure chamber. As the pressure in chamber 28 is at atmosphere, or just enough above atmospheric pressure to bring about circulation of steam through the radiator, the end of which is open to the atmosphere, the rod 37 does not have to be closely packed in its gland 38. If the operating rod extended, for example, directly from the atmosphere into the high pressure chamber through a wall of such chamber, the packing which would be required in order to prevent leakage of the high pressure steam, would have to be such as to materially affect the freedom of movement of the rod and consequently diminish the sensitiveness of the controller to temperature fluctuations. By having two consecutively operating valves, 35, 36, spring 47 may be comparatively light, which is a further factor in the sensitiveness of the controller. Spring 47 is located on the outside of the instrument so that it is not subject to the deteriorating influences of high temperature steam.

While the invention has been shown and described in a preferred embodiment, it is realized that changes might be made in the construction of the regulator without departure from the principles of the invention. It is the intention, therefore, to cover the invention both in the preferred embodiment shown and also with all modifications within the scope of the appended claims.

I claim:

1. In combination with the steam train pipe and radiator of a railway car heating system, a steam regulator provided with a high pressure chamber communicating with the train-pipe, a low pressure chamber communicating with the radiator and a port between said chambers, a valve operating rod, a main valve slidable on said rod, a pilot valve fixed to the end of the rod, a bell crank to impart reciprocating movements to the rod and a thermostat to operate the bell crank.

2. In combination with the steam train pipe and radiator of a railway car heating system, a steam regulator provided with a high pressure chamber communicating with the train-pipe, a low pressure chamber communicating with the radiator and a port between said chambers, a valve operating rod, a main valve slidable on said rod, a pilot valve fixed to the end of the rod, a bell crank to impart reciprocating movement to the rod, a thermostat to operate the bell crank in the valve closing direction and a spring to operate the rod in the direction to open the valves.

3. In combination with the steam train pipe and radiator of a railway car heating system, a steam regulator provided with a high pressure chamber communicating with the train pipe, a low pressure chamber com-

municating with the radiator and a member provided with a bore forming a port between said chambers, a reciprocating valve operating rod provided with guide ribs for guiding the rod in said port, and with guide ribs of less radial depth, a main valve slidably arranged on said second mentioned guide ribs, a pilot valve fixed to the end of said operating rod and thermostatically actuated mechanism for imparting reciprocating movements to said operating rod.

4. In combination with the steam train pipe and radiator of a railway car heating system, a steam regulator provided with a high pressure chamber communicating with the train pipe, a low pressure chamber communicating with the radiator and means constituting a port between said chambers, a valve operating rod extending through the low pressure chamber and into the high pressure chamber, a main valve slidably arranged on said rod, a pilot valve fixed to the end of the rod and mechanism for imparting reciprocating movements to the rod comprising a thermostatic member and a housing for said member provided with an outlet for water of condensation, but which otherwise completely encloses the thermostat.

5. In combination with the steam train pipe and radiator of a railway car heating system, a steam regulator provided with a high pressure chamber communicating with the train pipe, a low pressure chamber communicating with the radiator, and means constituting a port between said chambers, a valve operating rod extending through the low pressure chamber and into the high pressure chamber, a main valve slidably arranged on said rod, a pilot valve fixed to the end of the rod and mechanism for imparting reciprocating movements to the rod comprising a thermostatic member, a housing for said member provided with an outlet for water of condensation, but which otherwise completely encloses the thermostat, a bell crank interposed between the thermostat and rod and a spring which is flexed when the rod is moved to close the valve.
